CORDLESS ELECTRIC SADIRON

Harry E. Lutton, Waynesburg, Pa.

Application June 18, 1936, Serial No. 85,996

2 Claims. (Cl. 219—25)

My invention relates generally to a cordless electric sadiron, and particularly to an arrangement of this character involving an iron stand to which the cord is attached, instead of to the iron itself, and an electric sadiron including contacts exposed on its exterior and connected to its heating element, which contacts engage other contacts on the stand when the sadiron is disposed on the stand in the proper position, whereby the sadiron is heated during its positioning on the stand, and when removed from the stand, is free of the usual iron cord, during the ironing operations.

An important object of the present invention is to provide an arrangement of the character indicated above, which is simple, efficient, and relatively inexpensive, and which greatly facilitates ironing operations.

Other important objects of my invention will be apparent from a reading of the following description taken in connection with the drawings, wherein for purposes of illustration I have shown a preferred embodiment of my invention.

In the drawings:—

Figure 1 is a general top plan view of the embodiment, portions of the sadiron being cut away to disclose the exteriorly exposed contacts thereon engaged with the supply contacts of the stand.

Figure 2 is a side elevational view of Figure 1. Figure 3 is a bottom plan view of the stand showing the removable plate which when removed exposes the contact mechanism for adjustment and repair.

Figure 4 is a side elevational view of the body portion of the sadiron with the handle removed.

Referring in detail to the drawings, the numeral 5 generally designates the stand which for convenience may be shaped in the general outline of the sadiron which is generally designated 6 and be provided with a suitable number of props or legs 7 which depend from its underside and adequately support the stand on a surface.

The stand includes the fluted or corrugated floor 1 which is open as indicated by the numeral 8 at the rear end and closed on its opposite side by the longitudinal walls 9 and 10 which follow the contour of the stand and of the iron and merge into opposite sides of the tip portion 11 in which is embedded the pilot light 12 in front of which are the openings 13 and 14 exposing the contacts 15 and 16 which are to be engaged by the plug on the end of the energizing iron cord (not shown).

In accordance with the present invention the

sadiron 6 is provided with a conventional electrical heating element which is generally designated 17 and which has instead of the usual contact mechanism, contacts 18 and 19 which are exposed at the opposite sides of the body of the sadiron as shown in Figure 1 and to which the opposite ends of the heating element 17 are connected.

These contacts 18 and 19 are positioned so that when the sadiron 6 is placed on the floor 1 and pushed up toward the vertex end of the stand, the contacts 18 and 19 will engage curved spring contacts 20 and 21 which extend from the side walls 9 and 10 of the stand and have longitudinal portions 22 and 23 which are mounted 15 in channels 24 and 25 by dielectric blocks 26 and 27. The channels have their forward ends leading into an enlarged transversely elongated recess 28 in which are mounted bifurcated contacts 29 and 30 which are respectively connected to the 20 plug contacts 15 and 16. Also mounted in the recess 28 is a yoke 31 which is of dielectric character and carries the contacts 32 and 33, which are initially prevented from touching the contacts 29 and 30 with which they are opposed, 25 by the helical spring 33 which is suitably engaged with the wall of the recess 28 between the contacts 29 and 30 and with a central portion of the yoke 31 as shown in Figure 3. The forward ends of the contacts 22 and 23 are connected by 30 corresponding wires 34 and 35 with the contacts 32 and 33.

A yoke actuator which is generally designated 36 projects upwardly from the yoke 31 and about the level of the floor 1 of the base and into a 35 position to be engaged by the tip of the sadiron in the manner indicated in Figure 1, and forwardly displaced by the pushing of the sadiron by the operator toward the left hand end of the base as shown in Figure 1, to a position in which the contacts 32 and 33 engage the contacts 29 and 30 and close the electrical circuit to the supply line and thereby energize the heating element 17 of the sadiron as long as these positions are maintained. When the sadiron has been 45 sufficiently heated, the same is removed and the heating element thereof deenergized simply by moving the iron from the switch actuating position to a right hand position on the base or removed from the base.

A horseshoe-shaped plate which is generally designated 37 is attached by screws or the like 38 to the bottom of the stand at the tip end thereof to conceal the switch mechanism and the contacts, and to protect the same, while rendering the 55

same readily accessible for replacement or repair.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

10. What is claimed is:—

1. In combination, an iron stand including a sadiron receiving trough in its top and a switch mechanism on said stand and comprising a pair of horizontally spaced stationary contacts, a pair of movable contacts engageable with the stationary contacts and normally disengaged therefrom, a V-shaped operating element for the movable contacts positioned horizontally of the trough in the path of the iron and engaged by the point thereof during a forward sliding movement of the iron along the trough to close the switch.

path of the iron and engaged by the point thereof during a forward sliding movement of the iron along the trough to close the switch and spring means yieldably separating the contacts.

2. In combination, an iron stand including a 5 sadiron receiving trough in its top, and a switch mechanism on said stand comprising a pair of horizontally spaced stationary contacts, a pair of movable contacts engageable with the stationary contacts and normally disengaged therefrom, a 10 V-shaped operating element for the movable contacts positioned horizontally of the trough in the path of the iron and engaged by the point thereof during a forward sliding movement of the iron along the trough to close the switch.
